Attorney

UNITED STATES PATENT OFFICE.

CHARLES MOLINE, OF MULTNOMAH, OREGON.

PLUG.

Application filed May 7, 1926. Serial No. 107,441.

This invention relates to improvements in plugs and has particular reference to an electric plug commonly employed to connect a flexible cord to a socket or receptacle.

5 The principal object of this invention is to produce a plug which may be attached to any standard socket or receptacle with a minimum amount of effort and in the least possible time in counterdistinction to a common plug which has to be screwed into the receptacle.

10 Another object is to produce a device of this character which may be employed with any standard form of receptacle and one which will not require any instructions in order for a person to use the same.

15 A still further object is to produce a device of this character which is simple in construction and, therefore, one which can be manufactured at a reasonable cost.

20 Other objects and advantages will be apparent during the course of the following description.

25 In the accompanying drawings forming a part of this specification and in which like numerals are employed to designate like parts throughout the same,

30 Figure 1 discloses a socket with my device in position therebelow and showing in dotted lines the position my device will assume when engaged in the receptacle,

35 Figure 2 is a cross section taken on the line 2—2 of Figure 3,

40 Figure 3 is a vertical cross section of a portion of the socket with my device applied thereto, and

45 Figure 4 is an enlarged fragmentary detail view showing the manner in which the springs of my device engage one of the receptacle contacts.

50 At the present time, the receptacles and sockets are provided with a threaded contact piece into which a bulb or plug is adapted to be screwed. This screwing operation is a tedious one, particularly if the socket has a shade positioned thereon or if the socket is elevated to such a position that a person has to reach in order to screw the plug into the socket.

55 I have, therefore, provided a plug which may merely be pushed into the socket and one which will engage the threads firmly enough to produce a good contact. It will

be readily seen that the act of pushing the plug into the socket is much quicker than 55 the screwing operation and one which may be performed with the least amount of physical effort.

In the accompanying drawings wherein for the purpose of illustration is shown a 60 preferred embodiment of my invention, the numeral 5 designates the shell of a standard socket which socket is provided with an insulated lining 6.

65 At 7 I have shown a threaded contact member mounted upon an insulating support 8 carried within the shell 5, which insulating support also carries a contact 9. The structure thus far described is common to all sockets and forms no part of my invention.

70 Referring now to Figure 3, the numeral 11 designates the body of my plug to the end of which is secured a contact 12 and to the side thereof a metallic sleeve 13 having 75 spring contacting members 14 secured thereto. The head of the plug is designated at 16 and is provided with the customary prongs 17 and 18 which are adapted to be secured to an electric cord and, in turn, have 80 their ends engage contacts 19 and 21, respectively, which are, in turn, connected to the contacts 12 and the metallic sleeve 13. The result of this construction is that when the plug having a cord attached thereto is inserted in a socket by merely pushing the same into the socket, contact is made between the threaded portion 7 and the springs 14 and also between the contacts 9 and 12, thus completing the circuit to the cord so 85 90 that the current delivered by the socket may be used as desired.

95 It is to be understood that the form of my invention herewith shown and described is to be taken as a preferred example of the same, and that various changes in the shape, size and arrangement of parts may be resorted to without departing from the spirit of the invention or the scope of the subjoined claim.

100 Having thus described my invention, I claim:

In an electric plug, a base, a contact positioned upon the end of said base, a metallic sleeve surrounding a portion of said base, a 105 plurality of springs secured to said metallic

sleeve and adapted to contact the threaded portion of an electric socket, a removable head, contacts carried by said head, other contacts arranged within said base and connected to the first mentioned base contact and the sleeve respectively, said head carried contacts being adapted to complete a circuit from said head to the first mentioned base contact and threaded portion of the electric socket through the medium of the other base contacts and springs respectively. ¹⁰
In testimony whereof I affix my signature.

CHARLES MOLINE.
